UNITED STATES PATENT OFFICE.

JEANNETTE W. NESMITH, OF GILPIN COUNTY, COLORADO.

OINTMENT.

No. 851,306.

Specification of Letters Patent.

Patented April 23, 1907.

Application filed January 13, 1906. Serial No. 295,850.

To all whom it may concern:

Be it known that I, JEANNETTE W. NESMITH, a citizen of the United States, residing in the county of Gilpin and State of Colorado, have invented certain new and useful Improvements in Ointments or Salves, of which the following is a specification.

This invention relates to ointments or salves and consists in certain new and useful salves adapted to be used for healing diseased and abnormal tissue by application to, or near to, the same; such salves being suitable for treating, for instance skin diseases and subcutaneous disorders. For this purpose I admix with an oil or greasy excipient a suitable quantity of powdered pitchblende. Pitchblende is an ore of uranium and besides the mildly radio-active uranium itself, it contains radium compounds and a number of other radio-active components not definitely identified; all perhaps produced by the disintegration of the uranium molecule. In a finely powdered state, it produces a continual stream of emanations of rays or corpuscles, or both, capable of producing profound chemical and physical changes in substances exposed to the same. In contact with, or proximity to, the animal body, it produces healing changes in diseased and abnormal tissues, the emanations while steady and continuous not being so strong as to be dangerous. A salve containing pitchblende applied to the body maintains a mild, continual stream of emanations of great curative properties.

To manufacture such salve, I take a quantity of pitchblende and reduce the same to a fine powder. To this I add an ointment vehicle like lanolin, or other fatty or oleaginous substances of a fluent nature in quantity sufficient to produce a pasty ointment or salve, the consistency being regulated to that suitable for application to the portion of the body to be treated. A mixture of clay and glycerin, or similar substances, may be used with the powder to produce a salve of convenient consistency.

A suitable composition may be made by mixing 50 parts by volume of powdered pitchblende with 20 parts of a wax and 30 parts of paraffin oil.

What I claim is:

1. A topical remedy comprising powdered pitchblende and an ointment vehicle, substantially as described.

2. A topical remedy comprising powdered pitchblende and lanolin, substantially as described.

3. A topical remedy comprising a powdered mineral containing radium compounds in small quantity and an ointment vehicle adapted to form a salve therewith.

Signed at Central City in the county of Gilpin and State of Colorado this 8th day of January A. D. 1906.

JEANNETTE W. NESMITH.
